UNITED STATES PATENT OFFICE.

RUSSEL FRISBIE, OF CROMWELL, CONNECTICUT.

IMPROVEMENT IN BOILERS FOR TOY STEAM-ENGINES.

Specification forming part of Letters Patent No. 122,593, dated January 9, 1872.

To all whom it may concern:

Be it known that I, RUSSEL FRISBIE, of Cromwell, in the county of Middlesex and State of Connecticut, have invented certain new and useful Improvements in Boilers for Toy Steam-Engines; and I do hereby declare that the following is a full, clear, and exact description thereof, whereby a person skilled in the art can make and use the same, reference being had to the accompanying drawing and to the letters of reference marked thereon.

My invention relates to those small boilers which are heated by means of a lamp; and its object is to provide a strong and safe boiler with a bottom, where the heat is applied, sufficiently thin to be quickly and easily heated, so as to generate steam with rapidity.

In the accompanying drawing, *a* shows the body of the boiler, partly cut away to show the construction better. *b* is the bottom plate,

shown in section. The body of the boiler is formed of cast metal—generally of iron, and the bottom is of wrought or plate iron, cast into it. The plate is cut circular, or of any desired shape, and placed in the mold, when the top is cast onto it so as to embrace the edge of the plate and hold it fast. In this manner I secure a strong boiler, to which the parts of the engine can be easily attached, as shown in the drawing, and one which can be quickly heated to raise steam.

Claim.

What I claim as my invention is—
The cast boiler with a plate bottom, constructed substantially as herein described.

RUSSEL FRISBIE.
